UNITED STATES PATENT OFFICE.

AUGUST W. KURZ, OF NEW YORK, N. Y.

VAULT-HEAD.

1,149,652.

Specification of Letters Patent. Patented Aug. 10, 1915.

Application filed December 6, 1911. Serial No. 664,237.

To all whom it may concern:

Be it known that I, AUGUST W. KURZ, a citizen of the United States, residing in the borough of Manhattan, city, county, and 5 State of New York, have invented certain new and useful Improvements in Vault-Heads, of which the following is a specification.

The main object of this invention is to 10 provide a vault head consisting of a main member and a cover, the main member being provided with seats to support the cover in its normal spanning position and the cover being loosely connected to the main member by means of a locking device, said locking device forming no part of the supporting means when the cover is in its normal position.

Another object of the invention is to 20 provide a vault head of very simple construction in which the cover is at all times loosely interlocked with the main member so that it may be swung from its closed to its open position but cannot be detached or wholly 25 withdrawn from the main member.

Other equally important objects and advantages of the invention will appear hereinafter.

In the drawings, Figure 1 is a plan view 30 of a vault head constructed in accordance with my invention; Fig. 2 a transverse vertical sectional view on the line II-II of Fig. 1; Fig. 3 a similar view of a portion of the vault head the cover being shown in 35 its raised or open position; Fig. 4 a transverse vertical sectional view of a portion of a vault head showing a slightly different arrangement of the means for locking the cover to the main member; and Fig. 5 a detail sectional view of a portion of a main member showing a slightly different form of cover supporting lug.

Referring to the various parts by numerals, 1 designates the main member which is 45 formed with an upstanding rectangular flange 2 which surrounds a correspondingly shaped manhole, and with a horizontal base flange 3 extending outwardly from the lower edge of the flange 2. This base flange is 50 adapted to rest upon a suitable support, such as the masonry surrounding a basin opening or sewer inlet or vent. The flange 2 of the main member is provided near its forward wall with the inwardly extending lugs 55 4 on which the forward edge of the cover

rests when it is in its normal or spanning position. The side members of the flange 2 are provided adjacent the rear member of the upstanding flange, on their inner surfaces, with cover supporting lugs 5. The 60 upper surfaces of the cover supporting lugs shown in Figs. 1 and 2 are inclined rearwardly and downwardly, for a purpose which will hereinafter appear; and the rear member of the upstanding flange is formed 65 with the recess 6 at the rear ends of the cover supporting lugs 5 to permit any dirt which may drop on the cover supporting lugs to be forced rearwardly from said lugs and down through said recesses. 70

The cover 7 is provided along its side edges, at the rear ends thereof, with the depending feet 8; and along its rear edge with the depending flange 9. The flange 9 is adapted to bear squarely against the inner 75 surface of the rear member of the flange 2 when the cover is in its normal spanning position, as shown clearly in Fig. 2. The lower surfaces of the feet 8 are downwardly and rearwardly inclined to correspond with 80 the inclination of the upper surfaces of the cover supporting lugs 5 so that the tendency of the cover when it is thrown to its normal spanning position will be to ride down said inclined upper surfaces of the supporting 85 lugs to its normal seating position, thereby bringing the cover flange 9 against the inner surface of the rear member of the upstanding flange of the main member. The feet 8 of the cover are formed with the large openings 10, said openings registering with the recess or channel in the under side of the body of the cover, as shown clearly in Fig. 2. Extending through these openings and 90 transversely of the main member is a locking rod 11, said rod extending across the manhole and being permanently secured to the side members of the upstanding flange 2. This rod is below the body of the cover and is not engaged thereby when the cover is in 95 its normal spanning position, so that it will not receive any of the strains brought upon the cover, said strains being taken up entirely by the lugs 4 and 5 on the main member. The feet 8 extend to the rear edge of 100 the cover and the supporting lugs 5 are engaged by said feet where said lugs join the rear member of the upstanding flange. The interlocking rod 11 is located a suitable distance forward of the rear member of the 105

110

upstanding flange 2 and the apertures through the feet 8 permit the cover to be moved forwardly away from the flange of the main member sufficiently to permit it to be swung upwardly and rearwardly to its open position, as shown in Fig. 3.

It is manifest from the construction described that the cover cannot be tilted upwardly by any pressure brought thereon along its rear edge, all of said pressure being taken up by the supporting lugs 5 without in the least tending to tilt upwardly the forward edge of the cover. It is also manifest that the interlocking rod 11 will be free of all strains brought on the cover and will not serve as a supporting means for the cover when it is in its normal spanning position.

In Fig. 4 the recesses 10^a in the feet 8^a are wholly below the body of the cover; and the upper surfaces of the supporting lugs 5^a are horizontal. The operation of the construction shown in Fig. 4 is substantially the same as that shown in Figs. 2 and 3. In this construction the rear flange 9 of the cover is dispensed with.

In the construction shown in Fig. 5 the upper surfaces of the supporting lugs 5^b incline forwardly and downwardly; just the reverse of the inclination of the corresponding lugs shown in Fig. 2. In this view is also shown a pin 11^a carried by the main frame and adapted to extend inwardly through the opening in the adjoining foot of the cover. It will, of course, be understood that two of these pins might be used, one extending inwardly from each side flange of the main member. The pin 11^a may be secured to the frame in any suitable manner.

It will, of course, be understood that the construction shown and described, and embodying my invention may be varied in many details without departing from the invention and I do not wish to be limited to any particular details of construction except, of course, as said details may be made the subject matter of specific claims.

From the foregoing it is manifest that I provide an exceedingly simple, cheaply constructed, and efficient vault head wherein the parts may be very strongly constructed. It is also manifest that the cover will be loosely interlocked with the main member and cannot be detached or wholly removed therefrom.

What I claim is:

1. A vault head comprising a main member formed with cover supporting lugs, a cover formed with depending feet adapted to engage the supporting lugs upon the main member, apertures formed in said feet and an interlocking rod connected to the main member and extending through the apertures in said feet, said rod permitting the front edge of the cover to be swung

upwardly from the main member and preventing the complete removal of the cover from the main member.

2. A vault head comprising a main member formed with a cover supporting lug, a cover formed with a depending foot adapted to bear on the cover supporting lug of the main member, a transverse aperture in said foot and a rod carried by the main member and extending through said aperture, said aperture being larger than the rod and the walls of said aperture being out of contact with the rod when the cover is in its normal spanning position, whereby the cover may be bodily shifted and then swung upwardly at its forward edge and the rod will lock it to the main member and prevent its detachment from the main member.

3. A vault head comprising a main member formed with cover supporting lugs, a cover formed with depending feet adapted to rest on said lugs when the cover is in its normal spanning position, said feet being formed with transverse apertures, an interlocking rod connected to the main member and extending through the apertures in the cover feet, said rod loosely interlocking the cover with the main member and being so placed that it will be out of contact with the cover when said cover is in its normal spanning position.

4. A vault head comprising a main member formed with cover supporting lugs, a cover formed with depending feet at the rear edge thereof and adapted to rest on the supporting lugs, the rear edges of said feet being adapted to lie close to the adjacent wall of the main member when the cover is in its normal spanning position, the cover feet being formed with transverse apertures, an interlocking rod carried by the main member and extending through the apertures in the cover feet, said rod being materially smaller than said apertures and free of the walls of said apertures when the cover is in its normal spanning position, said apertures permitting the cover to be bodily shifted and then swung upwardly at its forward edge.

5. A vault head comprising a main member formed with cover supporting lugs having their upper surfaces inclined, a cover formed with depending feet at the rear edge thereof and adapted to rest on the supporting lugs, the under surfaces of said feet being inclined to correspond with the inclination of the supporting lugs, the rear edges of said feet being adapted to lie close to the adjacent wall of the main member when the cover is in its normal spanning position, the cover feet being formed with transverse apertures, an interlocking rod carried by the main member and extending through the apertures in the cover feet, said rod being

materially smaller than said apertures and free of the walls of said apertures when the cover is in its normal spanning position, said apertures permitting the cover to be 5 bodily shifted and then swung upwardly at its forward edge.

6. A vault head comprising a main member formed with cover supporting lugs having their upper surfaces inclined rearwardly and downwardly, a cover formed with depending feet at the rear edge thereof and adapted to rest on the supporting lugs, the rear edges of said feet being adapted to lie close to the adjacent wall of the main 15 member when the cover is in its normal spanning position, the cover feet being formed with transverse apertures, an interlocking rod carried by the main member and extending through the apertures in the 20 cover feet, said rod being materially smaller than said apertures and free of the walls of said apertures when the cover is in its normal spanning position, said apertures permitting the cover to be raised and then 25 swung upwardly at its forward edge.

7. A vault head comprising a main member formed with cover supporting lugs adapted to support the cover in its normal spanning position, a cover formed with a 30 transverse aperture near one end, interlocking means carried by the main member and

projecting into said aperture, the aperture in the main member being substantially larger than the interlocking means, the walls of said aperture being out of contact with 35 the interlocking means when the cover is in its normal spanning position whereby the cover will be capable of a lateral bodily movement and an upward swinging movement, the interlocking means preventing the 40 complete detachment of the cover from the main member.

8. A vault head comprising a main member having an upstanding flange, a cover fitting in said upstanding flange with horizontal apertures near its rear edge and below the upper surface of said cover, a horizontal rod fixed to the main member and extending loosely through said apertures to lock the cover to the main member, said 45 apertures permitting the cover to be lifted at its forward edge to free it from the upstanding flange of the main member and to be moved bodily forwardly to free the rear edge from the flange of the main member. 50

In testimony whereof I hereunto affix my signature in the presence of two witnesses.

AUGUST W. KURZ.
